UNITED STATES PATENT OFFICE.

HANS H. E. R. TIEDEMANN, OF DETROIT, MICHIGAN.

PRINTING AND CUTTING MACHINE.

1,144,924.

Specification of Letters Patent. Patented June 29, 1915.

Application filed November 27, 1914. Serial No. 874,259.

To all whom it may concern:

Be it known that I, HANS H. E. R. TIEDEMANN, a subject of the Emperor of Germany, residing at Detroit, in the county of Wayne and State of Michigan, have invented certain new and useful Improvements in Printing and Cutting Machines; and I do hereby declare the following to be a full, clear, and exact description of the invention, such as will enable others skilled in the art to which it appertains to make and use the same.

This invention relates to machines for printing and cutting wrapping paper for business houses, and one of the principal objects of the invention is to provide a simple device which can be used for printing and cutting different widths of paper from the same printing roll.

Another object of the invention is to provide means whereby paper of different widths may be printed from a single printing roll, and means being also provided whereby the printing of either the narrow or the wide paper may be dispensed with, so that the paper will pass through the machine without printing whenever desired.

Still another object is to provide a machine for printing wrapping paper in desired lengths and in desired widths, and means being provided for cutting the paper at any required length.

The foregoing and other objects may be attained by means of the construction illustrated in the accompanying drawings, in which,

Figure 1 is a side elevation of a printing and cutting machine made in accordance with this invention, Fig. 2 is a top plan view of the same, Fig. 3 is a sectional view taken on the line 3—3 of Fig. 2, and Fig. 4 is a sectional view taken on the line 4—4 of Fig. 2.

Referring to the drawing, the numeral 1 designates a box or casing in which the mechanism is mounted, said casing having two hinged members 2 and 3, connected to the casing by hinges 4 and 5, and said hinged members having a knife or cutter 6 and 7 disposed in an opening 8 or 9 adjacent a cross beam 10.

A roll of narrow paper 11 is mounted in a bar 12 having notches 13 therein to receive the pintles of the roller core, said bar being connected to three uprights on opposite sides

of the box or casing 1, said uprights being designated as *a*, *b*, and *c*. The cross bar 12 is connected to the uprights by suitable bolts or rivets 14. A cross bar 12^a is connected to said upright bars *a*, *b*, and *c* at their upper ends, and said cross bar is also provided with notches 13^a. A roll of comparatively wide paper 11^a is mounted in the bar 12 in the notches 13^a.

A printing roller 15 having type or a plate 16 connected thereto is mounted in the upright bars *b* and an inking roller 17 is also mounted in the uprights *b* and is in contact with the printing roller 15. The narrow web of paper from the roll 11 passes up a guide 18 on the platen roller 19 and from thence between said platen roller and type roller 15, over a roller 20 and up adjacent to the knife 6 where it is led out of the casing into position to be used. 75

The web of paper *a* from the roll 11^a, and of greater width than the roll 11, is fed up over a platen roller 20 mounted in notches 20^a in the bar 12^a, said paper passing over the platen roller 20 and adjacent to the printing roller 15 where it is printed and led down through a guide 22. From the guide 22 the web passes under the guide rollers 23 and under the roller 24 and up and over the roller 25 and out in contact with the knife 7. A crank handle 26 connected to the shaft of the printing roll may be used for feeding the paper to the printing roll and to the cutting knife. Whenever it is desired to print only from the wide roller 11^a, the platen 19 is adjusted in one of the notches 13^a at each side of the casing away from the printing roll 15 and when it is desired to only print the narrow paper, the platen roller 20 may be adjusted in one of the notches 20^a in the bar 12^a. 90

If it is desired to feed the paper without printing or cutting, it will be obvious that the platens may be thrown away from the printing roller, and that the knives may be thrown out of operation by swinging the members 2 and 3 on their hinges. 95

From the foregoing it will be obvious that a printing and cutting machine made in accordance with this invention is comparatively simple in construction, is reliable and efficient in use, can be manufactured at low cost and is quick and easy to make the required adjustments. 105

Various changes may be made in the de- 110

tails of construction without departing from the spirit and scope of the invention as defined in the claims.

What is claimed is:—

5. 1. A machine for printing and cutting wrapping paper comprising a casing, a central and side vertical standards secured to the bottom of said casing, upper and lower horizontal supporting rods secured to said standards, the ends of the lower supporting rods having rolls of paper of different widths rotatably mounted thereon, platen rollers mounted on the upper supporting rods near their ends, a printing roller rotatably mounted on said central support near the upper end thereof and being in alinement with said platen rollers, an inking roller mounted on said central support, the top of said casing having a pair of 10 parallel slots, knives secured adjacent to said slots, guide rollers secured to the inside of said casing, whereby the webs from the rolls of paper can be brought between said platen rollers and printing roller through 15 said slots and in engagement with said knives.
20. 2. A machine for printing wrapping pa-

per comprising a casing, a central standard secured to the bottom of said casing, side standards secured to the bottom of said casing and being parallel with said central standards, upper and lower supporting rods secured to said standards, a printing roller rotatably mounted on the upper portion of said central standards, said lower supporting rods having rolls of paper of different widths rotatably mounted thereon at a point near their ends, platen rollers rotatable on said upper supporting rods at a point near their ends, guides for the webs of said paper rolls secured to said platen rollers, the upper face of said rods near their ends being notched whereby said platen roller can be brought in or out of engagement with said printing roller and thereby allowing or 45 keeping the webs of said paper rolls from being printed.

In testimony whereof I affix my signature in presence of two witnesses.

HANS H. E. R. TIEDEMANN.
